UNITED STATES PATENT OFFICE

2,341,418

DRILL JIG

Dorothy G. Atkins, Groton, Conn.

Application July 27, 1942, Serial No. 452,507

6 Claims. (Cl. 33—189)

The present invention relates to new and useful improvements in jigs adapted for use in laying out and marking drill holes in work in exact position with relation to each other, such as the locating and marking of the centers of holes that are to be drilled in a circle in the work and the invention has for its primary object to provide a layout and drill jig embodying a protractor by means of which the holes to be drilled may be accurately marked in their desired relation.

A further object is to provide a device of this character of simple and practical construction, which is efficient and reliable in use, relatively inexpensive to manufacture and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout and in which:

Figure 1 is a plan view.

Figure 2 is an edge elevational view.

Figure 3 is a fragmentary plan view with the guide for the slidable leg of the tool broken away.

Figure 4 is a fragmentary sectional view taken substantially on the line 4—4 of Figure 3.

Figure 5 is a fragmentary sectional view taken substantially on a line 5—5 of Figure 1.

Figure 6 is a similar view taken substantially on a line 6—6 of Figure 1.

Referring now to the drawings in detail wherein for the purpose of illustration I have disclosed a preferred embodiment of the invention, the numeral 5 designates one leg of the tool having a head 6 at one end thereof substantially in the form of a T-square, the leg being substantially rectangular in cross section and the head 6 having one edge indicated at 7 curved in a semi-circle and formed on its upper surface with a raised flange 8 with graduations 9 marked thereon representing 180 degrees of a circle.

A second leg is designated at 10 likewise of rectangular shape in cross section and is slidably mounted between a pair of segmental plates 11 and 12 secured together by screws 13.

The head 6 is formed with an opening 13 and the plate 11 is formed with a stud 14 rotatably mounted in the opening and secured therein by a nut 15 threaded on the stud and bearing against the rear face of the head 6 as shown to advantage in Figure 4 of the drawings. The end of the stud is pointed as shown at 16 which

may be used as a center punch for centering the tool in the center of the circle of holes to be marked in the work. One edge of the plate 11 is also curved as shown at 17 conforming to the inner edge of the flange 8.

The plate 12 is formed with a flared opening 18 constituting a window opening behind which the leg 10 is slidable and the wall of the opening 18 is formed with a mark 19 extending in the plane of the straight edge of the plates 11 and 12, as well as with the straight edge of the head 6, when the face and head are aligned and the mark 19 is adapted to register with the graduations 20 formed on the upper surface of the leg 10. The leg 10 is secured in a slidably adjusted position between the plates 11 and 12 by a set screw 21 carried by the plate 12.

A pointed marker 22 is formed with a hollow externally threaded shank 23 having a slot 24 therein for slidably receiving the leg 5, the marker being held in adjusted position on the leg by means of a nut 25 threaded on the shank.

The outer end of the leg 10 is formed with an opening 26 in which a marking punch 27 is positioned having a head 28 thereon, the punch being held in the opening by a set screw 29.

The curved side edge of the plate 12 is also provided with a mark 30 in line with the graduations in the flange 8.

With the parts secured in assembled relation as shown it will be apparent that the leg 10 extends transversely of the graduations 9 of the flange 8 so that one edge of the leg aligns with said graduations during the swinging movement of the leg with respect to the head 6.

It is believed the details of construction, manner of use and advantages of the device will be readily understood from the foregoing without further detailed explanation.

Having described the invention, what is claimed as new is:

1. A drill jig comprising a leg member having a flat head integrally formed at one end, said head having an opening and provided with graduations concentric with the opening, a flat guide pivotally mounted in the opening and adapted to lie flat against the head, a second leg slidably mounted in the guide and intersecting the axis of the opening, means for securing the second leg and the guide in adjusted angular position relative to the first leg, and punches carried by each leg.

2. A drill jig comprising a leg member having a flat head integrally formed at one end, said head having an opening and provided with grad-

uations concentric with the opening, a flat guide pivotally mounted in the opening and adapted to lie flat against the head, a second leg slidably mounted in the guide and intersecting the axis of the opening, a prong on the guide adapted to engage the work to form a pivot for the legs, means for securing the second leg and the guide in adjusted position relative to the first leg, and punches carried by each leg.

3. A drill jig comprising a leg member having a flat head integrally formed at one end, said head having an opening and provided with graduations concentric with the opening, a second head member having a stud pivoted in said opening and pointed at its end, a second leg slidably mounted in said second head member transversely of the axis of the stud, said second leg also having graduations, a window opening in the second head member behind which the last-named graduations are exposed, a fixed mark on the second head member adapted to register with the graduations of the first head, a fixed mark on the second head adjacent the window opening for cooperation with the graduations on the second leg, means for securing the second leg in adjusted position and punches carried by each leg.

4. A drill jig comprising a T-shaped member including a leg and a head, said head having a curved edge, a flange on one surface of the head conforming to the curved edge and having graduations, a second T-shaped member including a head and a leg slidably mounted therein and having a working engagement with the gradu-

tions on the flange, means pivotally connecting the heads with the second leg intersecting the axis of the pivot means, and a punch carried by each leg.

5. A drill jig comprising a T-shaped member including a leg and a head, said head having a curved edge, a flange on one surface of the head conforming to the curved edge and having graduations, a second T-shaped member including a head and a leg slidably mounted therein and having a working engagement with the graduations on the flange, means pivotally connecting the heads with the second leg intersecting the axis of the pivot means, said second-named head having a sight opening and said second-named leg having graduations exposed in said opening, means securing the heads in adjusted position, means securing the second leg in adjusted position, and a punch carried by each leg.

10 6. A drill jig comprising a T-shaped member including a leg and a head, said head having a curved edge, a flange on one surface of the head conforming to the curved edge and having graduations, a second T-shaped member including a head and a leg slidably mounted therein and having a working engagement with the graduations on the flange, a stud pivotally connecting the heads, said second leg intersecting the axis of the stud, a nut threaded on the stud securing the heads in adjusted position, means securing the second leg in adjusted position in the second head, and a punch carried by each leg.

DOROTHY G. ATKINS.
